UNITED STATES PATENT OFFICE.

STEPHEN R. S. UFFORD, OF BATAVIA, ASSIGNOR OF ONE-HALF TO JAMES M. INNES, OF AURORA, ILLINOIS.

PILLOW-SHAM HOLDER.

SPECIFICATION forming part of Letters Patent No. 288,515, dated November 13, 1883.

Application filed June 21, 1883. (No model.)

To all whom it may concern:

Be it known that I, STEPHEN R. S. UFFORD, of Batavia, in the county of Kane and State of Illinois, have invented certain new and useful Improvements in Pillow-Sham Holders; and I do hereby declare the following to be a full, clear, and exact description of the invention, such as will enable others skilled in the art to which it appertains to make and use the same.

My invention relates to an improvement in pillow-sham holders, the object of the same being to provide a device of this character which shall combine simplicity and economy of construction with durability and efficiency in use; and with these objects in view my invention consists in certain details of construction and combinations of parts, as will be hereinafter described, and pointed out in the claims.

20 In the accompanying drawings, Figure 1 is a view of my improvement in its elevated position. Fig. 2 is a view thereof in section. Fig. 3 is a detached view of the bracket.

A represents the head-board of a bedstead, 25 to which are secured the pillow-shams B. At a suitable distance below the shams B are secured the brackets C, which are provided with the slots or grooves a, running across the inner faces thereof, and also with the central perforations, in which are adapted to fit the outer ends of the sectional cross-bar D. This bar is preferably made in two sections connected by a metallic tube, E, to which one section is rigidly secured. Within this tube 30 and between the ends of the two sections of the cross-bar D is placed a spiral spring, F. Near the outer ends of the cross-bar D is secured the wire frame G, one side of which is adapted to fit in the slot or groove a, formed 35 on the inner face of the bracket C. One end of the said cross-bar is provided with a washer, H, located between the bracket C and frame G, the spiral spring F tending to keep the said washer against the bracket.

40 It will now be seen that by this arrangement and construction of parts the device is self-locking, the spiral spring F having a constant tendency to separate the two sections of the cross-bar, thereby keeping the washer H 45 up against one bracket and the side of the frame against the other bracket, the said

frame, when turned, entering the slot or groove a in the bracket from the pressure of the spring. It will be seen that the slot runs parallel with the head-board, thereby adapting 55 itself to keep the frame in an elevated position when in the groove. If the frame is in its raised position and it is desired to lower it, it is simply necessary to press inwardly the projecting end of the cross-bar on the locking 60 side thereof, which presses that section of the bar inwardly and releases the frame from the groove a, and allows the frame to be lowered, the sham resting thereon. As the pillows prevent the frame from lowering a sufficient distance to enter the groove, it (the frame) is always ready to be raised, and when again elevated enters the groove a, as before stated, and cannot be released by any sudden jar or movement—as, for instance, by turning over 70 in bed.

By providing each bracket with the groove a the bar may be taken out and turned around, thereby rendering it capable of being manipulated from either side of the bed, the washer 75 H preventing the frame from locking on the other side, and the parts being retained in their proper relative position by means of the projection e, traveling in the slot d, formed in the metal tube. My invention is simple in 80 construction, is of few parts, can be manufactured at a small initial cost, and is adapted to be applied to any bedstead.

It is evident that slight changes in the construction and relative arrangement of the different parts might be resorted to without departing from the spirit of my invention. Therefore I would have it understood that I do not limit myself to the exact construction shown and described, but consider myself at liberty 90 to make such changes and alterations as fairly fall within the spirit and scope of my invention.

Having fully described my invention, what I claim as new, and desire to secure by Letters 95 Patent, is—

1. In a pillow-sham holder, the combination, with supporting-brackets, one of which is provided with a groove, of a sectional cross-bar provided with a spring to enable the bar 100 to be contracted and expanded in length, the ends of said cross-bar being journaled in said

supporting brackets, and the pillow-sham frame having its arms rigidly secured to the ends of the cross-bar, the parts being constructed and arranged substantially as described, to adapt one end of the frame to be removably secured within the groove in the supporting-bracket, substantially as set forth.

2. In a pillow-sham holder, the combination, with the brackets C, provided with the grooves a, of the yielding cross-bar D, jour-

naled in said brackets, the frame G, and washer H, all of the above parts combined and adapted to operate as described.

In testimony whereof I have signed this specification in the presence of two subscribing witnesses.

STEPHEN R. S. UFFORD.
